US0D1049634S

(12) **United States Design Patent** (10) **Patent No.:** **US D1,049,634 S**
(45) **Date of Patent:** **** Nov. 5, 2024**

(54) **ZIPPER BAG**

(71) Applicant: **Hangzhou Baike Electronic Technology Co., Ltd.**, Hangzhou (CN)

(72) Inventor: **Haidie Xu**, Hangzhou (CN)

(73) Assignee: **Hangzhou Baike Electronic Technology Co., Ltd.**, Hangzhou (CN)

(**) Term: **15 Years**

(21) Appl. No.: **29/850,281**

(22) Filed: **Aug. 18, 2022**

(51) LOC (14) Cl. **03-01**

(52) U.S. Cl.

USPC **D3/301**; D9/705

CLAIM

The ornamental design for a zipper bag, as shown and described.

DESCRIPTION

FIG. 1 is a front perspective view of a zipper bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlarged view of FIG. 1.

In the drawings, the dash-dot-dash broken lines represent a sectional designation that forms no part of the claim.

1 Claim, 9 Drawing Sheets
